UNITED STATES PATENT OFFICE.

EDWARD R. KNOWLES, OF BROOKLYN, NEW YORK, ASSIGNOR TO THE
MUTUAL ELECTRIC MANUFACTURING COMPANY, OF NEW YORK.

ARMATURE-WINDING FOR DYNAMO-ELECTRIC MACHINES.

SPECIFICATION forming part of Letters Patent No. 396,941, dated January 29, 1889.

Application filed December 3, 1885. Renewed December 21, 1888. Serial No. 294,284. (No model.)

To all whom it may concern:

Be it known that I, EDWARD R. KNOWLES, a citizen of the United States, residing at Brooklyn, in the county of Kings and State 5 of New York, have invented a certain new and useful Improvement in and Method of Winding Armatures, of which the following is a full, clear, and exact description.

This invention relates to certain improvements in the disposition of the wires of the armature of a dynamo-electric machine, by which I effect a considerable saving of wire and labor and am enabled to greatly facilitate the winding operation, at the same time 15 securing compactness, symmetry of shape, and perfect balance.

My invention consists in an armature with a double set of coils arranged in groups whose coils or loops are symmetrically arranged on 20 each side of a given diameter, the inner end of one loop being connected to the outer end of the next loop, thereby obtaining a continuous winding.

In the accompanying drawings, in the several figures of which like parts are designated by similar letters of reference, Figures 1 and 2 are front and rear end views of the armature, showing the method of winding. Fig. 3 is a side view, showing the shape and 25 30 position of one of the wire loops of which the winding is made up; and Fig. 4 is a sectional view of the armature, showing the winding-blocks and insulating material.

The wire is put on in the form of loops, as 35 shown in Fig. 3, the open corners of which are all brought to the front of the machine, but are arranged alternately on opposite parts of the same face. As shown in the drawings, four double groups of wires are employed, 40 with eight loops in each group. The groups are arranged at angles of forty-five degrees with each other. More or less groups may be employed, if desired, and in that case their angular positions must correspond to their 45 number.

The method of connecting the wire loops, as clearly shown in the drawings, is as follows: The inner end of each loop, as of loop 50 a b, is carried across either over or under the

next loop, c d, and brought up to the outer 50 end of the loop, e f, next but one to it. In like manner the inner end of this third loop, e f, is carried across the loop, g h, next to it, and carried to the outer end of the second loop, j k, from it. These contiguous ends are 55 then soldered together, the ends of the wire having been previously stripped of the insulation. This system is carried out all around the armature, as shown, until the whole series of loops are connected, forming a double and 60 endless coil, which, when rotated in a magnetic field, gives rise to currents that may be taken off by commutator-brushes. The commutator—in this case a thirty-two-leaved one—has each leaf connected with one of the soldered joints of the coil. If the field is so arranged as to have its opposite poles at N and S, the commutator and brushes must be arranged to take off the current from points as near as may be at right angles to the line 70 connecting N and S.

It will be observed that no attempt is made to secure diametric winding, but, on the contrary, that my method is one that, in general terms, maintains the numbers of the groups 75 of wires parallel to the particular diameter. I have ascertained that the polar regions of the field extend over a sufficient arc of the circle of the armature to render this method of group winding perfectly effectual. 80

The armature is a hollow cylinder with openings A A A A for ventilation in its ends. To keep the wires away from the center, so as to leave these openings partly or entirely free for the circulation of air, they are diverted from a straight line, as shown. To effect this curving of the wires, I employ winding-blocks B B', which fit loosely upon the shaft C C of the armature, and when pushed into position for the winding operation surround the bosses D D', as illustrated by the position of block B, and the wires are then carried around the blocks. When the winding is finished, the blocks B B' are removed from the armature, and the wires, by their 95 natural stiffness, retain the position given them.

To perfectly separate the wires from the

metal of the drum, I employ some suitable insulating material; the arrangement and position of which are clearly shown by the dark lines *x x*.

5 What I claim as my invention, and desire to secure by Letters Patent, is—

1. An armature having its coils divided into a number of groups, each group consisting of a number of separate bobbins or wires, and 10 one-half of the bobbins in each group wound parallel to each other and parallel to and on one side of a given diameter, alternate bobbins in the several groups starting from opposite sides of the same end of the armature, 15 substantially as described.

2. An armature having its coils disposed around it in groups of parallel wires starting in alternation from opposite sides of the same end of the armature and similarly ending at the same end of the armature, the ends of the 20 said coils or bobbins of the several groups being connected in alternation, substantially as set forth.

In testimony whereof I have hereunto set my hand this 10th day of November, A. D. 25 1885.

EDWARD R. KNOWLES.
